WOMAN'S STOCKING

Aaron Burleson, Burlington, N.C., assignor to Burlington Industries, Inc., Greensboro, N.C., a corporation of Delaware

Filed Nov. 19, 1963, Ser. No. 77,493

Term of patent 14 years

(Cl. D47—7)

*Fig. 2.**Fig. 3.*

FIGURE 1 is a side elevational view of a woman's stocking showing my new design;

FIGURE 2 is a side elevational view of the top or welt part of the stocking showing the appearance of the welt in a flattened but essentially untensioned state; and

FIGURE 3 is an enlarged fragmental view of the welt design shown in FIGURE 2.

The dominant feature of the stocking shown herein resides in the welt portion which consists in a series of ribbed bands wherein the ribs of each band are angularly disposed in relation to the ribs of each adjacent band, so as to present a zigzag or herringbone effect of ribs, substantially, as shown.

I claim:

The ornamental design for a woman's stocking, substantially as shown and described.
